(57) **CLAIM**

The ornamental design for the two-level turntable storage device, as shown and described.

DESCRIPTION

FIG. 1 is a side elevational view of the two-level turntable storage device showing my new design.

FIG. 2 is a right lower perspective view thereof;

FIG. 3 is a side perspective view thereof, the side opposite being a mirror image of that shown;

FIG. 4 is a top plain view thereof; and,

FIG. 5 is a bottom plain view thereof.

The broken lines showing is included for the purpose of illustrating environment and forms no part of the claimed design.
